CONTAINER WITH LOCKING COVER FEATURE
Richard H. Oberreich, Indianapolis, Ind., assignor to
Crown Paper Box Corporation, Indianapolis, Ind., a
corporation of Indiana

Filed Oct. 21, 1965, Ser. No. 499,985
4 Claims. (Cl. 229—39)

ABSTRACT OF THE DISCLOSURE

A paperboard or corrugated box having a self locking top or cover. The cover has a flap which is resiliently biased against the inside of the box when the box is closed. At the inside of the box there are tabs which taper to guide the flap into locking position. In one alternative embodiment the flap is guided against the front of the box, while in another embodiment away from the front of the box.

This invention relates generally to containers and more particularly to a box formed of fiberboard or the like and having a self locking top or cover.

It is usual practice in the container field to staple, stitch, tape or rivet a fiberboard box top to close the box after it has been packed. Such procedure requires an additional step over and above the closing of the box and also requires additional labor, machines, material and expense. Consequently, a primary object of this invention is to provide an improved container which automatically locks in a closed position merely upon closure of the box top.

Another object of the invention is to provide an improved container.

Still another object of the invention is to provide improved closure means for a container.

A further object of the invention is to provide a container closure which reduces expense yet which provides a secure closure.

Related objects and advantages will become apparent as the description proceeds.

One embodiment of the present invention might include a box having a cover hingedly connected to the box, said cover being swingable to a closed box position, a flap hingedly connected to said cover, said flap having a recess therein, a tab extending inwardly from the inside of the box and engaging said flap at said recess when said cover is in said position.

The full nature of the invention will be understood from the accompanying drawings and the following description and claims.

FIG. 1 is a top plan view of a box blank showing it prior to folding it into the box of the present invention.

FIG. 2 is a perspective view of the box after it has been folded and glued from the blank of FIG. 1.

FIG. 3 is an enlarged perspective fragmentary view of a portion of the inside of the box of FIG. 2.

FIG. 4 is a section taken along the line 4—4 of FIG. 2 in the direction of the arrows.

FIG. 5 is a fragmentary plan view of an alternative embodiment of the invention and shows a box blank identical to the box blank of FIG. 1 except for an illustrated modification.

FIG. 6 is a perspective view similar to FIG. 3 but showing the alternative embodiment of FIG. 5.

FIG. 7 is a section similar to FIG. 4 but showing the alternative embodiment of FIGS. 5 and 6.

FIG. 8 is an enlarged vertical section through the closed box of FIG. 5.

2

FIG. 9 is an enlarged section taken along the line 9—9 of FIG. 8 in the direction of the arrows.

For the purposes of promoting an understanding of the principles of the invention, reference will now be made to the embodiment illustrated in the drawings and specific language will be used to describe the same. It will nevertheless be understood that no limitation of the scope of the invention is thereby intended, such alterations and further modifications in the illustrated device, and such further applications of the principles of the invention as illustrated therein being contemplated as would normally occur to one skilled in the art to which the invention relates.

Referring now more particularly to the drawings, there is illustrated a box blank 10 which includes first, second, third and fourth side walls 11, 12, 13 and 14. When the box blank is assembled into the box of FIG. 2, the side walls 11, 12, 13 and 14 are folded at 90 degree angles to one another and the flap 15 is adhered to the inside of the side wall 14. The bottom of the box is assembled by interlocking the flaps 17, 18, 19 and 20.

The box further includes a cover 25 which is hingedly connected at its edge portion 26 to the upper edge 27 of the side wall 11. The cover 25 has second and third edge portions 30 and 31 which overlie the upper edges 32 and 33 of the side walls 12 and 14 when the cover is closed. Hingedly connected to the side walls 12 and 14 are a pair of flaps 35 and 36, respectively. When the box is in assembled relation, the flaps 35 and 36 are folded down into the box and become a part of the side walls. A pair of tabs 40 and 41 are foldably connected to the flaps 35 and 36 along the lines 42 and 45. The tabs 40 and 41 are separated from the flaps 35 and 36 along the lines 46 and 47.

Thus, when the flaps 35 and 36 are folded down into the box to become a part of the side walls thereof, the tabs 40 and 41 are folded as shown in FIG. 2 to project inwardly toward one another. When the box is so assembled, the tabs 40 and 41 are canted or tapered as shown in FIG. 4. Each of the tabs 40 and 41 has a lower surface 50 which engages the side wall 13 and which is generally horizontal. The tabs 40 and 41 cant or are tapered away from the side wall 13 from the surfaces 50 to the upper surfaces 51 of the tabs 40 and 41.

A flap 60 is foldably connected to the cover 25 along the line 61. The foldable connection is a resilient one and is made in such a manner that the flap 60 resiliently bears against the side wall 13 of the box when the flap is placed in the box as shown in FIG. 2. As suggested in FIG. 4, the box is closed by inserting the flap 60 between the tabs 40 and 41 and the front side wall 13 and by pushing the flap 60 down between the side wall 13 and the tabs until the recesses 62 and 63 register with the tabs 40 and 41. The recesses 62 and 63 have respective surfaces 64 and 65 which engage the surfaces 50 of the tabs 40 and 41 to lock the box in a closed position. It will be noted that when the box is in such a closed position, the edge portions 30 and 31 of the cover prevent the cover from moving into the box by over-lying the edges 32 and 33 of the side walls while the engagement of the surfaces 50 with the surfaces 64 and 65 holds the cover in a locked position. FIG. 3 shows in more detail the manner in which the flap 60 is positioned between the tab 40 and the front side wall 13 for closing the box.

Referring now more particularly to FIGS. 5, 6 and 7, an alternative embodiment of the invention is illustrated which is identical to the above described embodiment except for the variations illustrated.

Referring to FIG. 5, the flap 35' which corresponds to the flap 35 has a tab 40' foldably connected thereto along

the line 42'. The tab 40' is separated from the flap 35' at 46'. Because of the modification in structure of the tab 40' and because of a corresponding or complementary modification of the opposite tab in the position corresponding to the tab 41, the operation of locking the box is different as illustrated in FIGS. 6 and 7 in that the flap 60' is cammed over the tabs when the box is closed instead of being received between the tab and side wall as shown in connection with FIGS. 1 through 4.

As shown in FIGS. 6 and 7, the tab of the alternative embodiment resiliently engages the side wall 13' of the box toward the box opening 75 and tapers away from the side wall 13' to the tab lower surface 50'. The tab 40' has a slightly different configuration than the tab 40 in that the tab 40' is triangular with the upper surface 100 engaging the front wall 13' all along the length of the upper surface 100. The flap 60' of the alternative embodiment of FIGS. 5, 6 and 7 is identical to the flap 60. As the cover is closed in the manner illustrated in FIGS. 6 and 7, the flap 60' is first cammed away from the side wall 13' until the surfaces corresponding to the surfaces 64 and 65 move beneath the respective surfaces 50' at which time the resilient connection of the flap 60' to the cover urges the flap against the front wall 13' with the tabs 40' and 41' received in the recesses of the flap 60'. The box of FIGS. 5, 6 and 7 is then retained in closed condition in the same manner as described above in connection with the embodiment of FIGS. 1 through 4 and as shown in FIGS. 8 and 9.

It will be evident from the above description that the present invention provides an improved container which automatically locks in a closed position merely upon closure of the box top or cover. It will also be evident from the above description that the present invention eliminates the necessity of stapling, stitching, taping or riveting the box in order to secure it in closed condition.

While the invention has been illustrated and described in detail in the drawings and foregoing description, the same is to be considered as illustrative and not restrictive in character, it being understood that only the preferred embodiment has been shown and described and that all changes and modifications that come within the spirit of the invention and the scope of the claims are also desired to be protected.

The invention claimed is:

1. In a box including four side walls which define an opening, a cover hingedly connected at one edge portion thereof to one of said side walls, said cover being swingable between an open box position and a closed box position closing said opening, said cover having a second and third edge portion thereof which overlie respective ones of said side walls when said cover is in said closed box position, said cover having a fourth edge portion remote from said first edge portion, a flap hingedly connected at a first edge thereof to said cover fourth edge portion, said flap having second and third edges extending from said first edge, said flap having a pair of surfaces thereon each facing toward said cover, a pair of tabs each extending inwardly from a respective one of said side walls and each engaging said flap at a respective one of said surfaces when said cover is in said closed box position, a second of the side walls of said box being spaced from the one side wall, said tabs having surfaces away from said opening which are adapted to engage said flap surfaces when said cover is in said closed box position, said tab surfaces resiliently engaging said second side wall of said box away from said opening and tapering away from said second side wall toward said opening, said flap being resiliently connected to said cover so as to be biased toward said second side wall and beneath said tabs when said cover is swung from said open box position to said closed box position, said tabs acting as guides to guide said flap between said tabs and said second side wall as said cover swings from said open box position to said closed box position.

2. In a box including four side walls which define an opening, a cover hingedly connected at one edge portion thereof to one of said side walls, said cover being swingable between an open box position and a closed box position closing said opening, said cover having a second and third edge portion thereof which overlie respective ones of said side walls when said cover is in said closed box position, said cover having a fourth edge portion remote from said first edge portion, a flap hingedly connected at a first edge thereof to said cover fourth edge portion, said flap having second and third edges extending from said first edge, said flap having a pair of surfaces thereon each facing toward said cover, a pair of tabs each extending inwardly from a respective one of said side walls and each engaging said flap at a respective one of said surfaces when said cover is in said closed box position, a second of the side walls of said box being spaced from the one side wall, said tabs having surfaces away from said opening which are adapted to engage said flap surfaces when said cover is in said closed box position, said tabs resiliently engaging said second side wall of said box toward said opening and tapering away from said second side wall away from said opening to said tab surfaces, said flap being resiliently connected to said cover so as to be biased toward said second side wall and beneath said tabs when said cover is swung from said open box position to said closed box position, said tabs acting as cams to cam said flap inwardly away from said second side wall as said cover swings from said open box position to said closed box position.

3. In a box including four side walls which define an opening, a cover hingedly connected at one edge portion thereof to one of said side walls, said cover being swingable between an open box position and a closed box position closing said opening, said cover having a further edge portion remote from said first edge portion, a flap hingedly connected at a first edge thereof to said cover further edge portion, said flap having second and third edges extending from said first edge, said flap having a pair of surfaces thereon each facing toward said cover, a pair of tabs each extending inwardly from a respective one of said side walls and each engaging said flap at a respective one of said surfaces when said cover is in said closed box position, a second of the side walls of said box being spaced from the one side wall, said tabs having surfaces away from said opening which are adapted to engage said flap surfaces when said cover is in said closed box position, said tab surfaces resiliently engaging said second side wall of said box away from said opening and tapering away from said second side wall toward said opening, said flap being resiliently connected to said cover so as to be biased toward said second side wall and beneath said tabs when said cover is swung from said open box position to said closed box position, said tabs acting as guides to guide said flap between said tabs and said second side wall as said cover swings from said open box position to said closed box position.

4. In a box including four side walls which define an opening, a cover hingedly connected at one edge portion thereof to one of said side walls, said cover being swingable between an open box position and a closed box position closing said opening, said cover having a further edge portion remote from said first edge portion, a flap hingedly connected at a first edge thereof to said cover further edge portion, said flap having second and third edges extending from said first edge, said flap having a pair of surfaces thereon each facing toward said cover, a pair of tabs each extending inwardly from a respective one of said side walls and each engaging said flap at a respective one of said surfaces when said cover is in said closed box position, a second of the side walls of said box being spaced from the one side wall, said tabs having surfaces away from said opening which are adapted

to engage said flap surfaces when said cover is in said closed box position, said tabs resiliently engaging said second side wall of said box toward said opening and tapering away from said second side wall away from said opening to said tab surfaces, said flap being resiliently connected to said cover so as to be biased toward said second side wall and beneath said tabs when said cover is swung from said open box position to said closed box position, said tabs acting as cams to cam said flap inwardly away from said second side wall as said cover swings from said open box position to said closed box position.
